UNITED STATES PATENT OFFICE.

POWHATAN J. WOOLDRIDGE, OF PEWEE VALLEY, KENTUCKY.

SAFETY APPARATUS FOR ELEVATORS.

Application filed June 13, 1919, Serial No. 303,890. Renewed November 1, 1922. Serial No. 598,438.

To all whom it may concern:

Be it known that I, POWHATAN J. WOOLDRIDGE, a citizen of the United States, residing in Pewee Valley, Oldham County, Kentucky, have invented certain new and useful Improvements in Safety Apparatus for Elevators, fully described and represented in the following specification and the accompanying drawings, forming a part of the

10 same.

The general objects of the invention are to discontinue propulsion of the car when a shaft door is opened with the car near a landing, or if the motive power has already 15 been cut off when the door is opened, to prevent starting the car in either direction until the door is closed; to make the means for shutting off power operative whether or not the car oscillates within reasonable limits as 20 it is being stopped; and to prevent opening the door except when the car is close to the landing.

A special object is to arrange parts of the mechanism located in the shaft within 25 very narrow limits in a direction perpendicular to the shaft wall.

Another particular object is to arrange the parts of the mechanism which are located both on the shaft and on the car so 30 that none of them extend at all into the clearance space between the car and the shaft unless the shaft door is opened.

Another object is to prevent improper contact between parts of the mechanism 35 carried by the shaft wall, and the car or parts carried on the car.

A further object is to simplify and improve the construction and operation of devices of this character in ways pointed out 40 hereinafter.

The accompanying drawings show one exemplifying embodiment of the invention. After considering this, persons skilled in the art will understand how the invention 45 may be embodied in other forms without departing from these principles, and I do not limit myself to details except as claimed.

Fig. 1 is a horizontal section through the shaft wall showing in plan a structure embodying my invention, fragments only of the shaft wall and car being shown.

Fig. 2 is an elevation of parts of the structure carried by the shaft wall looking outward from a position above the car, an 55 upper corner of one of the shaft doors being shown, and of safety mechanism carried by

the car in correct relation to the shaft parts, the car, however, being entirely omitted for the sake of clearness.

Fig. 3 is a vertical section of fragments 60 of the shaft wall and upper structure of the car, showing the safety mechanism in side elevation.

Fig. 4 is a view similar to Fig. 1, showing the parts in one active position. 65

Fig. 5 is an enlarged fragmentary detail of the safety door latch or check device.

Fig. 6 is an elevation of an elevator car equipped in accordance with my invention.

S is the shaft wall, D a horizontally sliding shaft door, and C the upper structure of 70 a car.

On the shaft wall, preferably above the door, is fixed a flat frame member 1 having a lower horizontal extension 2 provided with 75 a guide slot consisting of a horizontal portion 3 and an end portion 4 which is in the form of a substantially semi-circular curve. The lower end of frame member 1 is spaced slightly away from the wall by a block 5, and the 80 upper end is similarly spaced from the wall by horizontal strip 6 which lies against the wall. A cross-piece 7 secured to strip 6 carries hinge pins 8 on which is pivoted one end of the swinging safety or stop arm 9. At 85 an intermediate point on frame member 1 is secured a fulcrum stud 10 having an enlarged head 11. The stop arm operating lever 12 has a slot 13 embracing the fulcrum stud on which the lever may move pivotally 90 and also vertically and horizontally to a limited extent. The lower end of operating lever 12 is secured to a stud 14 on which is pivoted the hub of a cam 15 which has two arms 16 and 17. On the top of the door is 95 secured a cam operating arm 60. The end of stud 14 is extended inwardly toward the shaft wall and engages in slot 3. The hub of cam 15 also has an inwardly extending stud 18 engaging in slot 3. The lower end 100 of operating lever 12 is urged to inactive or "closed door" position by a spring 19.

The central part of lever 12 is straight and lies close to frame member 1 when in "closed door" position. At a moderate distance from each end the lever is bent outwardly and then bent again so that the upper and lower end portions of the lever are parallel to the middle portion, but lie normally farther outward from the shaft wall. 105 At the upper end of the lever is formed a cylindrical portion 25 which passes through

a hole 26 in safety arm 9. This hole is slightly larger than cylindrical member 25 sufficiently to permit said member to occupy different angular positions in the hole, one of these positions being shown in Fig. 2. Arm 9 terminates in an end portion 28 of reduced size which serves to directly actuate a circuit breaker rail carried on the car.

On the car, usually above the roof and secured to structural parts of the car is a frame 30, 31, 32, 33. Vertical rods 34 and 35 connect frame members 31 and 32, and frame member 33 braces member 32 and the upper ends of the rods. Circuit breaker operating rail 36 is provided with a sleeve 37 which has a pivotal bearing on rod 34. The sleeve is connected to the rail by flange 38. Preferably, the rail is an angle piece of L section, so that it consists substantially of two flat vertical members 39, 40, arranged at a right angle to each other. From a part of sleeve 37 extends an arm 45 carrying an insulating block 46, and on this is secured a metal contact 47. This movable contact cooperates with two separated fixed contacts 48, 49, from which conductors 50 lead. These conductors constitute a part of the controlling circuit of the car, or a special safety circuit so arranged that when it is interrupted by withdrawing contact 47 the power circuit of the car is interrupted and if desired a brake is applied. Rail 36 is provided at a convenient point with an eye 55 located between the meeting point of the rail members 39 and 40 and the pivot axis 34. A spring 56 is connected at one end to this eye, and at the other end to an arm 57 extending from frame member 32, the eye 55, pivot axis 34 and point of spring connection with arm 57 being arranged so that they are all in line when rail 36 is midway between its two extreme positions shown in Figs. 1 and 4, respectively. The spring thus acts as a yielding detent and operating device to retain the rail in either of its extreme positions, and when it has been moved slightly beyond the central position in either direction to urge it to complete that movement.

Rail 36 may be as long as is necessary, to permit the shaft door to be opened with the car a reasonable distance above or below the landing, and also to permit a reasonable degree of oscillation of the car as it is being stopped, without interfering with the proper action of the safety mechanism.

When the floor of the car is reasonably near a landing, whether the power has been completely shut off or not, or if power has been completely shut off, whether or not the car is oscillating or drifting in either direction to a reasonable extent in stopping, if it is attempted to open the door D, cam operating arm 60 on the door first strikes cam arm 16 and moves the lower end of lever 12

to the right, Fig. 2. Studs 14 and 18 slide through horizontal slot 3; the cam 15 is prevented from rotating on its axis, and movement of the lever is resisted by spring 19. The initial left hand movement thus imparted to the upper end of lever 12 causes its cylindrical member to first exert a force tending to move safety arm 9 to the left against its pivot 8. Due to the angular relation of hole 26 in the arm to the pivot, the reaction of forces causes the lever to commence to swing outward about its pivot 8. In this movement hole 26 carries cylindrical end 25 of the lever through the arc of a circle centered at 8. As soon as arm 9 has moved slightly outward, the leverage effect of lever 12 upon it is greatly increased and the arm is easily carried through its complete arc of movement. As the upper end of the lever moves away from the shaft wall, the central portion of the lever moves outward to a smaller extent, this outward movement being accommodated by slot 13 travelling outward along fulcrum stud 10. At the same time since the lever also describes an arc about the axis 14, the slot travels upward about the stud. The connection of the lower end of the lever with stud 14 is sufficiently loose to permit the slight oscillation of the lever toward and from the shaft wall, this movement being reduced to a minimum at this point. In the outward swing of arm 9 its point 28 strikes flange 39 of rail 36 and moves the rail on its axis 34 until it passes its middle position. Spring 56 then urges the rail to complete its travel to the position shown in Fig. 4. At the first movement of rail 36, arm 45 takes the movable contact 47 away from fixed contacts 48 and 49 and the controlling or safety circuit is broken, discontinuing or preventing application of power to move the car in either direction. Continued opening movement of the door brings the end of stud 14 to the beginning of curved portion 4 of the guide slot. Stud 14 travels around this curved portion, cam 15 is permitted to rotate on its axis 14, and this movement is aided by the action of door arm 60 on cam arm 16. As the cam approaches the position shown in dotted lines in Fig. 2, door arm 60 is freed from the cam and the door may be opened to its full extent. The location of stud 14 in the end of curved slot 4 locks lever 12 against return pull of spring 19. Completion of the movement of rail 36 to the position of Fig. 4 in the meantime freed the end of arm 9 from the rail, and in the described movement of lever 12, arm 9 completed its movement to the position of Fig. 4. When the shaft door is closed the parts function in substantially reverse order. Door arm 60 first strikes cam arm 17 and commences to rotate the cam until stud 14 is nearly opposite the straight portion 3

of the guide slot. At this time spring 19 becomes effective to move lever 12, and the door, toward closed position. The upper end of lever 12 moves arm 9 back until its end 28 strikes flange 40 of rail 36 and moves the rail beyond its central position. Spring 56 thereupon completes movement of the rail and closes the control circuit at contacts 48 and 49. The arm is free from the rail and as the door approaches closed position, lever 12 moves the arm to its position of rest within the limits of the wall recess. When the door is completely closed, the parts have resumed their normal position shown in Fig. 2.

It is desirable in some cases to provide means to prevent opening the shaft door unless the car is reasonably near the landing. The invention comprises very simple and effective means for this purpose. A swinging detent member 70 is pivoted to the end of flat strip 6. The outer end of this member has a hook 71. A spring 72 coiled about the pivot urges member 70 toward active position. Near the pivot connection arm 70 has an offset lug 73. In certain cases this limits the extreme outward movement of arm 70 by striking the outer face of strip 6. Normally, member 70 is held back against the shaft wall by the rear face of safety arm 9, as shown in Fig. 1. In this position end 28 of arm 9 is separated considerably from hook 71. If it is attempted to open the door when the car is not within safety distance of the landing, a slight movement of the door brings arm 9 to the position shown in dotted lines in Fig. 1. Because of the separation of pivot centers of arms 9 and 70, at this point hook 71 engages end 28 of arm 9 and prevents further movement of the arm and further opening of the door. The amount of door opening permitted by this device may be very slight—only about an inch, or even less. To render the safety latch ineffective when the car is within safety distance of the landing, a rail 75 is located on the car adjacent the rail 36. Rail 75 is provided at one edge with a sleeve 76 having a pivotal bearing on rod 35. In normal position the rail rests against a stop 77 and is urged to this position by a spring 78. Rail 75 is usually considerably shorter than rail 36 and is preferably located vertically midway of rail 36, as shown. When the car is within safety range of the landing, this range being indicated by the length of rail 75, when the door is moved slightly away from closed position, hook 71 strikes rail 75 before it reaches the position shown in dotted lines in Fig. 1. At this time the hook is clear of the end 28 of arm 9. This position is shown in Fig. 4. Arm 9 can, therefore, complete its travel without interference by hook 71; the door may be fully opened and the normal safety

function of arm 9 is exercised as previously described.

In some cases, for instance when the door is slightly opened when the car is not near the landing, arms 9 and 70 may occupy the position shown in dotted lines in Fig. 1 as the car approaches. To prevent detent arm 70 from getting behind stop rail 75 in such a case, the stop rail is preferably provided at its upper and lower ends with rearwardly and laterally bent extensions 80. These are so arranged as to encounter the ends of the two arms in any of their positions from the idle position shown in Fig. 1 to the point where the arms lock as indicated in dotted lines, and to force the arms back and especially to force the end of arm 70 back so that the hook 71 rests properly against the outer surface of the stop rail.

It is also desirable in many cases to provide means for preventing damaging contact between arms 9 and 70 and parts of the car proper. For this purpose, the car is provided with a vertical guard rail 90 terminating in inwardly curved end portions 91. The end portions 91 are so arranged that whenever the arms extend in any of the positions just above described they will be wiped back by end portions 91 and will then slide along the straight face of rail 90 as the car passes, and any injury either to the arms or to parts of the car will be prevented. It will be evident that the curved members 80 of rail 75 and the guard rail 90 with its curved end members will only function when the door is improperly manipulated, and this is a rare occurrence.

In some cases the curved end portions 80 of stop rail 75 may be omitted. In that case the pivotal mounting of the rail is desirable to take care of certain abnormal conditions such as the following examples: If it is attempted to open the door when the car is fairly near the landing but outside the safety range, that is, so that the upper end of rail 75 is below a point opposite hook 71, or the lower end of the rail is above a point opposite the hook, the hook will pass above or below the end of the rail as the case may be in reaching the position shown in Fig. 1, where it locks the door against further movement. If at that time the car was moving slightly, sufficient to bring the rail opposite the normal position of the hook, the return movement of the hook when the door is fully closed would bring the hook into contact with the rear face of the rail. When the rail is pivotally mounted as described, this return movement of the hook causes the rail to move outward on its pivot against spring 78 until the hook passes the edge of the rail, whereupon spring 78 snaps the rail

back to normal position. Or if, when the door is opened, the car is within safety range of the landing but oscillating or drifting somewhat, the hook will strike 5 rail 75 and permit full opening of the door and the safety action of arm 9, but if the drifting movement of the car is sufficient to carry the upper or lower end of rail 75 below or above the end of the hook as the 10 case may be, the hook will pass beyond the rail until stopped by lug 73 striking strip 6. If the car then has a return drift or oscillation, the hook will then be brought again within the vertical limits of rail 75 15 and on closing the door will be permitted to return to normal position by the pivotal movement of the rail as above described.

It is to be especially noted that the invention permits such a design of parts of the 20 mechanism located on the shaft that they may be all located within a very narrow space perpendicular to the shaft wall. The space or recess provided for these parts may be made as small as $1\frac{1}{4}$ inches in the direction indicated, or even less. It is also to be noted that in the normal position of the 25 parts there is no part of the safety mechanism either on the shaft or the car which extends into the clearance space between the 30 car and the shaft wall. The normal or desired clearance limits between the car and the shaft are, therefore, not interfered with in any way.

When a car guard rail such as 90 above 35 mentioned is provided, with the curved or cam shaped ends 91, it is sometimes desirable to give to the portions of such ends at one side of the rail an additional rearward curvature as at 95. These portions are those 40 which are traversed by the end of hook 71. By this arrangement, as parts 95 of the rail are about to move out of contact with the hook, the hook is permitted to move outwardly somewhat farther than the end of 45 safety arm 9 which rests on the main surface of the cam ends 91. This additional outward movement of the hook gives added assurance that the hook will correctly engage with end 28 of the safety arm and 50 lock the door against further opening movement until stop rail 75 is properly positioned in relation to the arms, whereupon the arms will be acted upon and the door may be opened normally, as above described.

55 What is claimed is:

1. In safety mechanism for elevators, the combination with an elevator shaft, a shaft door, a car movable in the shaft and a control circuit including a circuit breaker, of 60 a vertical, movable rail carried by the car and connected with the circuit breaker, a horizontally swinging arm located on the shaft wall and adapted to cooperate with the rail when the car is near the landing, an approximately vertical lever connected with

the arm, and cooperative means carried by the lever and the shaft door to move the arm and operate the rail and circuit breaker when the door is opened with a part of the rail opposite the arm. 70

2. In safety mechanism for elevators, the combination with an elevator shaft, a shaft door, a car movable in the shaft and a control circuit including a circuit breaker, of 75 a vertical, movable rail carried by the car and connected with the circuit breaker, a horizontally swinging arm located on the shaft wall and adapted to cooperate with the rail when the car is near the landing, an approximately vertical lever connected with the arm, a controlling member for the lever pivotally connected to the lower end thereof, a guide for the controlling member comprising a straight portion and a curved detent portion, and a member carried by the 80 door to cooperate with said lever controlling member. 85

3. In a safety mechanism for elevators, the combination with an elevator shaft, a shaft door, a car movable in the shaft and a control circuit including a circuit breaker, of 90 a vertical, movable rail carried by the car and connected with the circuit breaker, a horizontally swinging arm located on the shaft wall and adapted to cooperate with the rail when the car is near the landing, an approximately vertical lever connected with the arm, a two-armed cam pivotally connected with the lower end of the lever, a guide comprising a straight portion and a curved detent portion, cooperating guiding means carried by the cam, and an arm carried by the door and cooperating with the cam between the arms thereof. 95

4. In safety mechanism for elevators, the combination with an elevator shaft, a shaft door, a car movable in the shaft and a control circuit including a circuit breaker, of 100 a vertical, movable rail carried by the car and connected with the circuit breaker, a horizontally swinging arm located on the shaft wall and adapted to cooperate with the rail when the car is within reasonable distance of the landing, an approximately vertical lever connected with the arm, a two-armed cam pivotally connected with the lower end of the lever, a guide comprising a straight portion and a curved detent portion, cooperating guiding means carried by the cam, an 105 arm carried by the door and cooperating with the cam between the arms thereof, and a spring urging the lever to closed door position. 110

5. In safety mechanism for elevators, the combination with an elevator shaft, a shaft door, a car movable in the shaft and a control circuit, of 115 a horizontally swinging safety arm pivoted in the shaft, a lever, a connection between the lever and the arm at a point angularly offset from the arm pivot, means 120

cooperating between the door and the lever to operate the lever, and safety mechanism including a circuit breaker in said control circuit carried by the car and arranged to cooperate with said arm.

6. In safety mechanism for elevators, the combination with an elevator shaft, a shaft door, a car movable in the shaft and a control circuit, of a horizontally swinging safety arm pivoted in the shaft, a lever, a connection between the lever and the arm at a point angularly offset from the arm pivot, means cooperating between the door and the lever to operate the lever, said means comprising a member movably connected to the lever and movable with it and a guide comprising a detent portion engaged by said member when the lever is in safety position, a spring urging the lever to normal position, and safety mechanism including a circuit breaker in said control circuit carried by the car and arranged to cooperate with said arm.

7. In safety mechanism for elevators, the combination with an elevator shaft, a shaft door, a car movable in the shaft and a control circuit of a horizontally swinging safety arm pivoted on the shaft wall and normally lying close against the wall, a substantially vertical lever normally lying closely parallel with the wall and having a connection with said arm at a point angularly offset from the arm pivot, a shifting fulcrum for the lever located on the shaft wall, a controlling member movably connected to the lower end of the lever, a guide engaged by the controlling member and comprising a straight portion and a detent portion, a member carried by the door to operate said controlling member, a spring urging the lever to normal position, and safety mechanism including a circuit breaker in said control circuit carried by the car and arranged to cooperate with said safety arm.

8. In safety mechanism for elevators, the combination with an elevator shaft, a shaft door, a car movable in the shaft and a control circuit, of operating mechanism located on the shaft wall comprising a horizontally swinging arm actuated by opening the shaft door, a vertical safety rail of considerable length mounted on the car to swing horizontally upon a long vertical bearing and arranged to be actuated by said safety arm when any point of said rail is opposite the safety arm, and a circuit breaker in said control circuit operated by said safety rail.

9. In safety mechanism for elevators, the combination with an elevator shaft, a shaft door, a car movable in the shaft and a control circuit, of operating mechanism located on the shaft wall in a very small space perpendicular to the wall and comprising a horizontally swinging safety arm actuated by opening of the shaft door, a vertical safety rail mounted on the car to swing hori-

zontally and arranged to be actuated by said safety arm when a part of the rail is opposite the safety arm, a circuit breaker in said control circuit operated by the safety rail, and means yieldingly holding the rail in either safety or normal position and urging the rail to complete its movement to either position when moved past mid-position in the corresponding direction.

10. In safety mechanism for elevators, the combination with an elevator shaft, a shaft door, a car movable in the shaft and a control circuit including a circuit breaker, of operating mechanism located on the shaft wall in a very small space perpendicular to the wall and comprising a horizontally swinging safety arm actuated by opening of the shaft door, safety door latch mechanism comprising a swinging latch arm pivoted on the shaft wall and controlled by movement of the safety arm, said latch arm comprising a hook adapted to cooperate with the end of the safety arm, a vertical stop-rail carried by the car and adapted to be engaged by said latch arm when the rail is opposite the arm and prevent latching engagement of said hook with the end of the safety arm, a vertical safety rail mounted on the car to swing horizontally and arranged to be actuated by said safety arm when a part of the rail is opposite the safety arm, and a circuit breaker operated by the safety rail.

11. In safety mechanism for elevators, the combination with an elevator shaft, a shaft door, a car movable in the shaft and a control circuit including a circuit breaker, of a horizontally swinging safety arm located on the shaft wall and operated by movement of the shaft door, a horizontally swinging latch arm located on the shaft wall and having a hook adapted to engage the end of the safety arm and prevent further movement of the door when the door is slightly opened, a vertical stop rail pivotally mounted on the car and adapted to engage the latch arm when the car is within safety distance of a landing and prevent latching engagement with the safety arm, and means yieldingly holding said stop rail in normal position, the pivotal mounting of said stop rail permitting return of the latch arm to normal position when it is beyond and opposite the stop rail.

12. In safety mechanism for elevators, the combination with an elevator shaft, a shaft door, a car movable in the shaft and a control circuit, of a horizontally swinging safety arm located on the shaft wall and operated by movement of the shaft door, a horizontally swinging latch arm located on the shaft wall and having a hook adapted to engage the end of the safety arm and prevent further movement of the door when the door is slightly opened, a vertical stop rail pivotally mounted on the car and

adapted to engage the latch arm when the car is within safety distance of a landing and prevent latching engagement with the safety arm, means yieldingly holding said stop rail in normal position, the pivotal mounting of said stop rail permitting return of the latch arm to normal position when it is beyond and opposite the stop rail, a vertical safety rail pivotally mounted on the car and extending above and below the ends of said stop rail, said safety rail comprising two angularly related flanges, the safety arm being arranged to cooperate with said safety rail between said flanges, and a circuit breaker in said control circuit operated by the safety rail.

13. In safety mechanism for elevators, the combination with an elevator shaft, a shaft door, a car movable in the shaft and a control circuit, of a swinging arm located in the shaft and arranged to project into the path of the car when in active position, means controlled by movement of the shaft door to operate said arm, a safety device including a circuit breaker in said control circuit on the car to cooperate with said arm, and guide devices located on the car to prevent damaging contact of the arm with the car.

14. In safety mechanism for elevators, the combination with an elevator shaft, a shaft door, a car movable in the shaft and a control circuit, of a swinging arm located in the shaft and arranged to project into the path of the car when in active position, means controlled by movement of the shaft door to operate said arm, safety mechanism on the car including a circuit breaker in said control circuit and a member to cooperate with said arm, said member having rearwardly curved upper and lower end portions to guide said swinging arm into proper relation to the car safety mechanism, and

additional guide devices located on the car to prevent damaging contact of the arm with the car.

15. In safety mechanism for elevators, the combination with an elevator shaft, a shaft door, a car movable in the shaft and a control circuit, of a swinging arm located in the shaft and arranged to project into the path of the car when in active position, means controlled by movement of the shaft door to operate said arm, and safety mechanism on the car including a circuit breaker in said control circuit and a member to cooperate with said arm, said member having rearwardly curved upper and lower end portions to guide said swinging arm into proper relation to the car safety mechanism.

16. Safety mechanism for elevators, including the following parts upon the wall of the elevator shaft, viz: a door latch and an actuating member; and the following parts on the elevator car, viz: means for releasing said door latch, and safety mechanism operable by said actuating member for preventing movement of the car; the said parts being so arranged that the shaft door cannot be opened except when the elevator is at or near the landing and that the elevator cannot be actuated when the shaft door is open, and being so located when in inoperative position that the parts upon the wall of the shaft lie wholly at one side of a vertical plane and that the parts located upon the elevator lie wholly upon the other side of said vertical plane.

In testimony whereof I have hereunto set my hand in the presence of two subscribing witnesses.
